Oscar L. Smith
BY R. F. Holmes
ATTORNEY

UNITED STATES PATENT OFFICE.

OSCAR L. SMITH, OF RYDAL, PENNSYLVANIA. ASSIGNOR TO PENN RIVET CORPORATION, OF PHILADELPHIA, PENNSYLVANIA, A CORPORATION OF VIRGINIA.

HAIR CURLER.

Application filed April 15, 1924. Serial No. 706,672.

To all whom it may concern:

Be it known that I, OSCAR L. SMITH, a citizen of the United States, residing at Rydal, in the county of Montgomery and 5 State of Pennsylvania, have invented an Improvement in Hair Curlers, of which the following description, in connection with the accompanying drawings, is a specification, like characters on the drawings re- 10 presenting like parts.

This invention relates to improvements in hair curlers for curling or waving hair, and more particularly has reference to hair curlers of the type comprising two arms 15 pivotally connected at one end and having a locking device for holding the free ends of the two arms in closed position when the hair has been wound upon one of the arms.

20 It has been proposed heretofore to make hair curlers from a single piece of metal one arm of which is flexible and springs away from the other arm to a limited degree, but in such proposed construction 25 the flexible arm is more or less in the way while the hair is being wound around the other arm. By pivotally connecting the arms as in the present device one arm may 30 be swung to such an angle to the other 35 that it will be entirely out of the way while hair is being wound upon the other arm.

In hair curlers of the type of the present invention the arm upon which the hair is wound should have a rounded contour that 35 is free from edges that might injure or break the hair wound thereon.

Having the above matters in mind, the present invention relates to a hair curler consisting of a hair receiving rod of rounded 40 contour in cross-section and having an end portion bent to form a pivot that extends through a flat arm of spring metal and pivotally secures the flat arm to the hair receiving rod.

45 The various features of the invention will best be made clear from the following description and accompanying drawings, wherein:

Fig. 1 is a perspective view of the hair 50 curler of the present invention with the pivoted arms disposed at an angle to each other.

Fig. 2 is a perspective view showing the 55 pivoted arms of Fig. 1 swung toward each other.

Fig. 3 on an enlarged scale shows the pivoted arms locked together with the hair to be curled in place between them; and,

Fig. 4 is a plan view of Fig. 3 without the hair between the arms.

In accordance with the present invention the hair receiving arm 1 comprises a stiff rod of rounded contour in cross-section and which is free from edges that might break or injure the hair wound thereon, and the 60 arm 2 is formed of flat spring metal that is bent outwardly so that it normally springs away from the hair receiving arm 1, as shown.

The arms are pivotally connected so that 70 one may be swung to different angular positions relative to the other. The pivotal connection between the two arms preferably is in the form of a stiff joint so that the arms 75 will remain at any angular position to which they are adjusted, and the pivotal connection is formed by bending an end portion of the rod 1 at right angles to the axis of the rod to form a pivot pin 3 that extends through a hole formed in the flat arm 2 80 near one end. The pivot pin 3 is secured in the hole of the flat arm by providing shoulders 4 and 5 upon the pin that engages the opposite faces of the flat arm. The end portion of the rod 1 provided with the pivot 85 pin is bent to form a bulging loop 6. This loop makes it possible to position the pivot pin 3 in substantial alignment with the axis of the rod 1 so that the flat flexible arm 90 will lie close to the rod 1, and it also avoids bending the rod 1 at a sharp angle in forming the pivot pin 3. The loop 6 is further desirable in that it forms a clearance space 95 between the arms 1 and 2 adjacent the pivot so that danger of the hair being caught between the two arms at the pivot is avoided, and by forming the pivot pin as an integral part of the rod 1 a simple and satisfactory construction is provided.

The flat flexible arm 2 is provided with a 100 locking end 7 which is preferably formed by a folded over portion at the free end of the arm. The locking means 7 has a notch 8 in the end portion 9 adapted to receive the end of the bar 1 and lock the bar to the 105 flexible arm with the hair to be curled confined between the arms as shown.

What is claimed is:—

1. A hair curler formed of a solid stiff hair receiving rod of rounded contour in 110

cross-section and presenting no edges liable to break or injure the hair wound thereon, and a separate flat arm of spring metal pivotally secured to said rod by a tight joint formed by bending a portion of the rod at right angles to its axis to form a pivot pin that extends through a hole in the flat flexible arm and is secured therein by shoulders on the pivot pin at the opposite faces of the flat arm, and a lock for connecting the free ends of the flexible arm and stiff rod.

2. A hair curler formed of a solid stiff hair receiving rod of rounded contour in cross-section and presenting no edges liable to break or injure the hair wound thereon,

and a separate flat arm of spring metal pivotally secured to the rod by an integral part of the rod consisting of an end portion of the rod bent to form a bulging loop 20 from which a portion of the rod extends at right angles to its axis to form a pivot pin that extends through a hole in the flat flexible arm and is secured therein by shoulders on the pivot pin at the opposite faces of the flat arm, and a lock for connecting the free ends of the flexible arm and stiff rod.

In testimony whereof I have signed my name to this specification.

OSCAR L. SMITH.
